UNITED STATES PATENT OFFICE.

WILLIAM S. WELLS, OF SOUTH BETHLEHEM, PENNSYLVANIA, ASSIGNOR TO BENJAMIN EASTWOOD COMPANY, OF PATERSON, NEW JERSEY, A CORPORATION OF NEW JERSEY.

LOOM.

Application filed August 31, 1923. Serial No. 660,293.

To all whom it may concern:

Be it known that I, WILLIAM S. WELLS, a citizen of the United States, residing at South Bethlehem, in the county of Lehigh and State of Pennsylvania, have invented certain new and useful Improvements in Looms, of which the following is a specification.

The present invention consists in certain improvements in looms for weaving in which the reed is arranged to yield rearwardly, the improvements having for their object to produce better weaving results to the end that blemishes incident to the placement of the filling will be practically absent from the woven goods; and to reliably cause stopping of the loom in case the reed is caused to recede to a predetermined extent due to the presence of a shuttle between it and the fell of the cloth when the reed is beating up the filling.

In the drawings,

Fig. 1 is a vertical sectional view of the front part of a loom embodying the improvements, the batten-including structure being back and the section being in a plane close to and at the near side of the nearer lay-sword;

Fig. 2 is a vertical sectional view through the batten and certain parts of the improved mechanism in the plane 2—2, Fig. 3;

Fig. 3 is a plan of the batten and the improvements; and

Fig. 4 is a vertical sectional view on line 4—4, Fig. 3 and showing the reed and other parts in the positions they assume when the reed recedes to an abnormal extent due to intervention of a shuttle between it and the fell of the cloth.

a is the loom frame; b the breast beam therein; c the knock-off shaft having a handle c' and forming the controlling member of a well-known means for stopping the loom and consequently the backward and forward motion of the batten-including structure, the normal position of said knock-off shaft when the loom is running being that shown in Fig. 1 and it being adapted to rotate clockwise in order to stop the loom; d is an arm affixed to and depending from and hence forming a part of the rocking structure constituted by the knock-off shaft; e is the lay or batten and f are the lay-swords adapted to be rocked backward and forward in the usual way from a suit-

able going part of the loom (not shown). The lay-swords are bent backward in the vicinity of the top surface of the batten to provide a recess f'; this is not material to the invention.

The reed structure comprises a lower rail g in which are set the lower ends of the reed dents h and also the usual glass-bar i back of these dents; a pair of brackets j having angular seats j' at their lower ends to which the rail g is bolted; and a tubular reed cap k in an underneath slot k' (Fig. 3) in which the top edge of the series of dents h (suitably united at their top ends to form said series) is held, the reed cap being secured to the brackets and the brackets being arranged to swing on a transverse axis parallel with the batten as follows:

Each bracket j is bent at j² to conform substantially to the bend-forming portions 75 of the adjoining lay-swords, and its upper end has a forward ear j³ arranged in a vertical plan and an inward web j⁴ which extends higher than the ear. The ear j³ has a hole to receive a bearing stud l on an angle 80 bracket m that is bolted to the adjoining lay-sword. A stud-bolt n is secured to and projects forward from the web j⁴ and on this by a nut n' the flat projection o' of a plug o, which is brazed in the end of the 85 reed cap, is secured. Thus the rail g, reed-cap, dents and brackets j are rigidly united to form the reed structure, which is adapted to swing forward and back on the pivots l. The webs j⁴ have bolted thereto the up- 90 standing counterweights p.

To the under side of the batten are secured by screws fixed elongated plates q each having at its rear end a depending stud q' and its forward end bent downward 95 at q². The stud affords a fulcrum for a bell-crank lever r having a forward short arm r' and a laterally projecting long arm r². To the short arm is pivoted the clevis of a stem s which is guided in the smaller 100 rear end of a tapering hole formed in a plug t screwed into portion q² of plate q; around the stem and compressed between its clevis and the plug is a spiral spring u. The long arm r² is connected by a link v with a stud 105 w depending from the rail g.

A dagger x is pivoted between its ends at the under side of the batten. In the normal slight movements of the reed structure the top surface of the dagger is wiped just 110

forward of a rearward slope x' thereof by a stud y projecting downward from the mentioned rail g , which thus maintains the point of the dagger elevated above the notched end portion d' of arm d , but if the reed structure is moved backward to an abnormal extent, as in Fig. 4, the dagger will fall into position to strike the portion d' of arm d on the next forward stroke of the batten, thus to cause stopping of the loom by the rocking of the knock-off shaft. When the reed structure is returned the parts y and x' by camming coaction return the dagger to normal position.

15 The reed structure is normally held by the toggle connection between it and the batten, afforded by levers r , springs u and links v , bearing against the vertical face of a recess e' cut in the back of the batten; the forward 20 pressure which the reed structure thus exerts may be varied by turning the screw plugs t .

Each time the batten moves forward in the beating-up stroke, the reed structure on impact with the fell A of the cloth may yield 25 rearwardly; the degree of resistance to such yielding, which of course is a factor in determining the density of the finished fabric, depends on the adjustment of the screw plugs t . In this yielding (due to mere impact with the cloth) the reed structure does 30 not recede so far as to cause the pivots (r^3) between lever arms r' and stems s to pass the positions where they would be aligned with said stems, and so when the batten recedes 35

the springs u return the reed structure into contact with the batten. If a shuttle should be left in the shed when the batten beats up its intervention between the reed and the fell A causes the reed structure to yield rearwardly to an abnormal extent (i. e., from 40 the dotted position in Fig. 1 to a position where pivot r^3 passes a straight line between pivot q' and the free end of member s) so that the springs u will now be active to 45 repress the reed structure from the dotted line to the full-line position in Fig. 4, releasing the dagger, which falls and on the next beat-up stops the loom as already stated.

50 Important and novel features of my invention are the following: First, though the springs u are always active to turn levers r (except when pivots r^3 are aligned with stems s), their pressure thereon is 55 always substantially constant because whatever energy each spring gains by compression is offset by decreased angularity of lever arm r' with respect to stem s , and whatever the spring loses by distension is offset by increased angularity of the said lever arm 60 with respect to the stem. In batten structures having reeds yieldable against the resistance of a spring there was heretofore no provision for maintaining the resistance 65 equitable. Secondly, in my reed structure the

mass represented by p (p above the fulcrum n') constitutes an offset or counterbalance to the mass represented by the reed proper, here the part of the reed structure below the fulcrum; reed structures have heretofore been constructed without any counterbalance to the inertia thereof so that not only had the spring to be strong enough to overcome the inertia of the reed structure at the backward limit of the batten's stroke 70 but at its forward limit two forces were active on the reed, i. e., that of the spring means tending normally to hold it forward or up to its work and that of its inertia. An object in constructing the reed to yield is to 75 allow it, by yielding, to compensate for conditions which would produce visible transverse blemishes in the fabric. My invention, on account of the reed being subject only to the force of a spring to hold it forward and 80 to such force being always applied as a substantially constant one rather than one which increases as the reed structure recedes, makes it possible to weave with substantially complete absence of such blemishes. Thirdly, I 85 employ a spring toggle between the batten-including and reed structures whereby so long as the reed is pressed back within a certain limit the toggle will return it, but if it exceeds such limit it receives an impulse 90 to move still further back, i. e., so as not to crowd the shuttle or other intervening obstruction against the fell A and incidentally cause stopping of the loom.

z designates a stop to limit the movement 100 of each lever r and consequently of the reed structure to the full backward position.

Having thus fully described my invention, what I claim as new and desire to secure by Letters Patent is:

1. In combination, the back-and-forth-moving batten-including structure of a loom, a reed movable back and forth therein, and movable means constituting a mass substantially equal to that of the reed and 110 resisting the back and forth movement of the latter in said structure due to inertia.

2. In combination, the back-and-forth-moving batten-including structure of a loom, and a reed-structure fulcrumed therein on a horizontal axis and having the portions thereof above and below its axis forming substantially equal masses, one of said portions having the reed-proper.

3. In combination, the back-and-forth-moving batten-including structure of a loom, a reed-structure fulcrumed therein on a horizontal axis and having the portions thereof above and below its axis forming substantially equal masses, one of said portions having the reed-proper, and means, on said reed-structure being turned in the direction to displace said portion rearwardly, to return the reed structure.

4. In combination, the back-and-forth-

moving batten-including structure of a loom, a reed-structure movable backwardly therein, and means to oppose substantially constant resistance to the reed-structure when the same is subjected to a backwardly displacing force.

5. In combination, the back-and-forth-moving batten-including structure of a loom, a reed-structure movable backwardly therein, and means to oppose substantially constant resistance to the reed-structure when the same is subjected to a backwardly displacing force including a spring tensioned by said force.

10 6. In combination, the back-and-forth-moving batten-including structure of a loom, a reed-structure movable backwardly therein, a lever fulcrumed in one structure and adapted to be moved by the other on its fulcrum when the reed structure is moved back, and a spring operatively engaged on the one hand with the lever eccentrically of its fulcrum and on the other hand with one of said structures and adapted to be 25 tensioned when the lever is so moved.

7. A loom including a back-and-forth-moving batten-including structure, a movable controlling member, a reed-structure yieldable backwardly in the first structure, and a dagger normally urged in the first 30 structure into position to engage and actuate said member but held by the reed structure against such movement, said reed-structure on backward yielding being adapted to release the dagger, and the dagger and reed-structure having camming surfaces adapted to wipe on each other to return the dagger from said position when the reed-structure, having yielded backward, is returned.

8. In combination, the back-and-forth-moving batten-including structure of a loom, a reed-structure movable backwardly therein, a lever operatively connected with each structure and a toggle spring connected to one structure and also connected to the lever eccentrically of the pivot by which the lever is connected to the latter structure.

45 In testimony whereof I affix my signature.

WILLIAM S. WELLS,
